UNITED STATES PATENT OFFICE.

AXEL EDMUND STIGBERG AND CHARLES BECHTOLD, OF BROOKLYN, NEW YORK.

DENTAL DIE-PUNCH.

1,228,617.

Specification of Letters Patent.

Patented June 5, 1917.

Application filed February 8, 1917. Serial No. 147,447.

To all whom it may concern:

Be it known that we, AXEL EDMUND STIGBERG, a citizen of the United States, and resident of 262 Fifty-first street, in the borough of Brooklyn, county of Kings, city and State of New York, and CHARLES BECHTOLD, a citizen of the United States, and a resident of 434 Himrod street, in the borough of Brooklyn, county of Kings, city and State of New York, have invented certain new and useful Improvements in Dental Die-Punches, of which the following is a specification.

This invention relates to punches and dies and especially to that class wherein the receiving plate contains a die beneath the plunger and is shiftable.

One advantage of this invention is to provide a punch wherein the plunger presses a cut piece of metal against a nameplate die in the same operation in which it cuts said piece.

Another advantage is to have a shiftable receiving plate by the shifting of which, pieces cut by the plunger may be immediately removed.

Another advantage is to have the nameplate die in the receiving plate to facilitate its removal or replacement.

Another advantage is to have a shiftable receiving plate which returns to normal position upon releasing the same.

Another advantage is to have a stripping plate above the die to remove the stock from the plunger.

Further advantages and possibilities will become apparent as the specification proceeds.

With the aforesaid advantages in view, the invention comprises the improvements hereinafter described, illustrated in the accompanying drawing and pointed out in the claims.

In the drawing, the same letter or number refers to the same parts in the several views.

Figure 1 is a top view of an apparatus embodying this invention with the punch frame and plunger omitted. Fig. 2 is a similar view of a part of Fig. 1. Fig. 3 is a vertical central sectional view of the left half of Fig. 1 when in position for operation. Fig. 4 is a vertical, longitudinal section of Fig. 1 when in position for operation. Fig. 5 is a view of the underside of a

piece of metal cut and stamped by the apparatus of the preceding figures. Fig. 6 is a sectional view of Fig. 5 embedded in material to which it imparts its shape.

In the practice of arts, as for example dentistry, it is usual to form pieces of metal to provide shape to subsequent hollow parts such as the suction space in hard rubber plates. This forming of the metal has been done by cutting or stamping out pieces of soft metal as 9' of the desired shape and then placing the same in a mold into which fluid rubber or similar material was to be poured.

If it was desired to have the name of the maker appear in the final product, it has heretofore been necessary to previously stamp this into the piece of soft metal by a separate operation, sometimes by a loose die.

Upon hardening of the rubber, as 12 on Fig. 5, the same was removed from the mold and the piece of formed metal 9' picked out. This latter operation would provide a hollow chamber in the rubber 9'.

It is intended to combine two steps in the above process by means of the present invention, namely the cutting out of the metal and the stamping of the name thereon.

A sheet of soft metal 9 is placed in position on ring die 2 and plunger 13 in frame 14 caused to descend. This will primarily cut a piece of the metal 9' of the shape shown in Fig. 5, and secondly, press the same down through space e upon die 3.

Plunger 13, when being withdrawn from space e, would ordinarily lift the sheet 9 from die 2, and to prevent this, stripping plate 4 has been provided.

If receiving plate 1 is then pushed to the position indicated at 1', the metal 9' and die 3 will assume the position indicated at 3' and 9'. The screw 10 is a backstop for 9, to positively carry 9' out to the dotted position, where the metal is easily picked off.

The receiving plate, which is slidably guided in base plate 5 has an arm 8 to which is attached spring 6, the latter being secured to screw 7 in 5. This will tend plate 1 and arm 8 to return to normal position if released when first drawn to position 1' and 8', plate 1 being rearwardly limited in movement by screw 11.

The counterbored seat c receives name die 3, and contains aperture b to facilitate removal or exchange of the die. The pin a

100

105

110

is provided to make the die 3 fit in but one position, and aids in securing the same in plate 1.

When the metal 9' comes from plate 1', it is indented by the die 3 on the underside, but when 9' is pressed into soft receptive material as at 12 in Fig. 6, the final product is a name in relief, shown in cross section.

Various modifications and uses of this invention are possible within its scope and spirit other than the specific use herein described.

Having thus fully described our invention, we claim:—

- 15 1. A punch including a slidable receiving plate arranged to reciprocate in a base plate, a rearward limit upon said plate adapted to abut said base plate, and a die mounted upon the same, a stop behind said die adapted to 20 retain in position products pressed upon said die during the reciprocation of said slidable plate, a reciprocating die adapted to coöperate with the die upon said receiv-

ing plate, and resilient means (slidable) retaining said plate with the said die thereon 25 in operative relation to said reciprocating die.

2. A punch including in combination a base plate housing a slidable plate, a die mounted upon said slidable plate, a ring die 30 mounted across said plate upon said base plate, a reciprocating die adapted to pass through said ring die and coöperate with the die upon said slidable plate, and resilient means retaining said slidable plate 35 and the die thereupon mounted in operative relation with said reciprocating die.

Signed at 132 Nassau street, in the borough of Manhattan in the county of New York, city and State of New York, this 6th 40 day of February, A. D. 1917.

AXEL EDMUND STIGBERG.
CHARLES BECHTOLD.
